UNITED STATES PATENT OFFICE.

EDWARD TURGEON, OF MINNEAPOLIS, MINNESOTA, ASSIGNOR OF ONE-HALF TO
SALISBURY & SATTERLEE CO., OF MINNEAPOLIS, MINNESOTA, A CORPORATION
OF MINNESOTA.

WIRE-COILING MACHINE.

Application filed April 20, 1923. Serial No. 633,478.

To all whom it may concern:

Be it known that I, EDWARD TURGEON, a citizen of the United States, residing in Minneapolis, county of Hennepin, and State of Minnesota, have invented certain new and useful Improvements in Wire-Coiling Machines, of which the following is a specification.

This invention relates to improvements in wire-coiling machines particularly adapted for use to wind hollow wire cables such as are commonly used in the manufacture of bed springs, etc., and more particularly relates to that part of such a machine known as the coil-forming head, through which the strands of wire are drawn for the purpose of equally spacing and guiding such wires in the formation and subsequent winding of the cable. Wire-coiling machines such as are commonly used at the present time require the use of a forming or central core around which the strands of wire are coiled in the winding of the cable. This core is usually drawn through a central aperture provided in the coil-forming head during the winding process, and when the cable has been wound to a predetermined length the core is returned to its normal or starting position and the completed cable cut off. Machines, as above described have a mechanism for returning the core to the starting position each time a cable has been wound. Such a machine is shown in my United States Patent 1,382,258, issued June 21, 1921.

By the employment of the novel coil-forming head feature in this invention, the usual core and its returning mechanism may be dispensed with, thus simplifying the construction of the machine and reducing to a considerable extent the manufacturing cost.

The particular object of this invention, therefore, is to provide an improved coil-forming head.

Other objects of the invention will more fully appear from the following description, and the accompanying drawings and will be pointed out in the annexed claims.

In the drawings, there has been disclosed a structure designed to carry out the objects of the invention, but it is to be understood that the invention is not confined to the exact features shown, as various changes

may be made within the scope of the claims.

In the drawings:

Figure 1 is a longitudinal sectional view 55 of a coil-forming head embodying my invention, showing the wires positioned therein for coiling;

Figure 2 is a plan view of Figure 1, showing the means provided for securing the 60 forming head to the frame of the machine;

Figure 3 is a view showing the coil starting needle or rod removed from the head;

Figure 4 is a cross-sectional view on the line 4-4 of Figure 2, showing the forming 65 head clamped in its supporting means; and

Figure 5 is a cross-sectional view on the line 5-5 of Figure 2 showing the rotatably mounted wire guiding collar positioned upon its bearing. 70

In the selected embodiment of the invention here shown for purposes of disclosure, there is illustrated a coil-forming head which is preferably clamped or secured to a suitable supporting member or arm 6, which in turn is secured to the frame, not shown, of any suitable wire-coiling machine to which the forming head may be adapted. 75

The coil-forming head consists preferably, of a cylindrical member 7 which is provided 80 with a plurality of spirally drilled apertures 8, adapted to receive the strands of wire therethrough and thus guide and space them during the cable winding operation. The member 7 is preferably fixedly mounted 85 upon a suitable sleeve 9, having an enlarged end portion 11. A flanged head 12, having a reduced bearing portion 13 is also secured to the sleeve 9 between the cylindrical member 7 and the shoulder 14, provided at one 90 end of the sleeve, as shown in Figure 1. Spaced apertures 15 are provided in the flanged head 12 adapted to receive the wires therethrough. An annular collar or ring 16 is preferably loosely mounted upon the reduced end portion 13 of the flanged head 12, 95

and functions as a means to guide the strands of wire from the apertures 15 to the spirally drilled apertures 8 in the cylindrical member 7. The collar 16 is preferably of hardened steel and is of less thickness than the length of the reduced bearing portion 13, thereby allowing it to freely rotate or change its position upon the bearing 100

portion 13 as the wires are drawn thereover in passing through the forming head during the cable winding or forming operation. By allowing the collar 16 to thus change its position relative to the flanged head 12, a greater wearing surface will be presented to the wires as a result of such wires constantly changing their point of contact upon the wearing surface of the collar, such action also preventing the wires from cutting grooves in the wearing surface of the collar.

The outstanding feature of this invention resides in the means provided for starting and forming the spirally wound hollow cable after the wires have been equally spaced by having been drawn through the coil-forming head, as hereinbefore described.

A coil starting pin or rod 17 having a suitable point 18 formed at one end thereof, as shown in Figure 3, is rotatably and removably mounted in the sleeve 9. Referring to Figure 1, and the dotted line showing in Figure 3, it will be noted that the end of the sleeve 9 through which the pin point 18 projects, is preferably tapered to substantially the same angle as that of the pin point 18, and that its outer conoidal surface merges with the pin point, thereby providing a continuous point from the tip of the point 18 to the end of the cylindrical member 7 adjacent the apertures 8. The enlarged projecting point thus formed provides a suitable form or core upon which the strands of wire are wound during the process of forming and winding the hollow cable, as shown at 19. The point 18 of the pin and also the conoidal end of the sleeve 9 are preferably hardened for the purpose of presenting a better wearing surface and also to prevent the wires from cutting grooves therein.

As is shown in Figures 1 and 2, a collar 21 is suitably secured to the pin 17, preferably by means of a set screw 22. An anti-friction thrust bearing 23 of ordinary construction is preferably positioned upon the pin between the enlarged end portion 11 of the sleeve and the inner face of the collar 21, thus allowing the pin to freely rotate within the sleeve 9 as a result of the frictional contact between the point 18 of the pin and the wires being coiled and formed thereon.

This frictional contact of the wires wears the point 18 quite rapidly, but whenever necessary, the pin can be easily and quickly removed from the head, and if the point is worn off or dulled, it can be ground down to the desired size. It is not necessary, however, to remove the pin very frequently as its rotation in the sleeve through contact with the wires eliminates considerable wear and lengthens the life of the point. The use of this removable pin makes it unnecessary to provide a point on the end of the sleeve which would wear rapidly on account

of the sleeve being stationary, and would necessitate the removal of the entire sleeve for re-grinding or repairing purposes.

Means are also provided for the purpose of preventing the pin 17 from becoming detached from the sleeve 9 when the cable is severed after having been wound to the desired length. It may be well to state that while the cable is being wound it is under a tensional strain, caused by the tension means provided for equalizing the tension of each wire before passing through the coil-forming head. Therefore, when the cable is severed while under such tension, a recoil will be effected in the unsevered portion of the cable. This recoil is sufficient to cause the pin 17 to be ejected from the sleeve 9, and it is therefore preferable to provide means whereby such ejection may be prevented.

An angular arm 24 is pivotally mounted upon the supporting arm 6 by means of a suitable pin or screw 25. The end portion 26 of this arm is provided with an open slot 27 adapted to straddle the pin 17 adjacent the collar 21 and thus prevent the pin from being ejected from the sleeve, as clearly shown in Figures 1 and 2. The other end of the arm 24 is adapted to engage a suitable stop pin 28 secured to the supporting arm 6. The arm 24 may be raised, as indicated in Figures 1 and 4, to permit the pin 17 to be removed from the sleeve 9 for the purpose of regrinding or reshaping the point after it has become damaged from wear, etc.

To start the forming and winding of the hollow cable, the wires are inserted in the coil-forming head, as indicated in Figures 1 and 2. They are then drawn therethrough a suitable distance and the ends of the wires secured to a suitable winding and gripping means, such as shown in my patent above referred to. As the wires are thus wound about the projecting point 18 of the pin and the tapered end of the sleeve 9, a perfectly formed hollow spirally wound cable is formed without the use of the central core heretofore employed in the manufacture of such cables. By the elimination of this central core the construction of the machine may be greatly simplified, and the cost of manufacture materially reduced.

I claim as my invention:

1. A coil-forming head having guides for strands and a core mounted in said head for rotation with the strands or coil thereon.

2. The combination with a coil-forming head having guides therein, of a core pin loosely mounted in said head for rotary and longitudinal movement and having a point for contact with the material being coiled.

3. The combination with a wire coil-forming head having a series of wire guides therein, of a core pin mounted in said head and having a tapered point around which

the wires are coiled, said pin being mounted for rotation with the coiling movement of the wires.

4. In combination with a coil-forming head having guides for the strands, and a tapered surface for contact with such strands, of a core pin mounted in said head and having a tapered point adapted to merge into the corresponding surface of said head.
5. In combination with a wire coil-forming head having guides for the strands of wire, and a tapered surface for contact with such strands, of a core pin mounted in said head and having a tapered point adapted to merge into the corresponding surface of said head, said pin being rotated in said head by contact of the wires with the tapered point thereof.

6. A wire coil-forming head comprising a member having spirally-formed wire guides therein and a tapered surface whereon the wires are directed by said guides, and a core pin mounted in said head and having a tapered point adapted to merge into the correspondingly tapered surface of said member.

7. A wire coil-forming head comprising a sleeve member having a tapered surface at one end whereto wires to be coiled are directed, a core pin having a tapered end mounted in said sleeve member against which tapered end the wires are held during the winding operation, said pin having a rotary movement in said sleeve member, and a thrust bearing provided between said pin and said sleeve member.

8. A wire coil-forming head having guides therein for the wire strands, a core

pin having a tapered end around which the wires are coiled, said pin being removable from the coil, and means preventing the premature discharge of said pin when the tension on the wire coil is released.

9. A wire coil-forming head having guides therein for the wire strands, a core pin having a tapered end around which the wires are coiled, said pin being removable from the coil, and means preventing the premature discharge of said pin when the tension on the wire coil is released, said means comprising a collar on said pin and an arm having an end to straddle said pin near said collar.

10. A wire coil-forming head having guides for wire strands and a removable core mounted in said head for longitudinal adjustment and for rotation as the wires are coiled thereon.

11. A coil-forming head having guides for strands and a core mounted in said head for longitudinal adjustment, and a tapered point around which the strands are coiled, said core being rotated in said head by contact of the strands with the tapered point thereof.

12. A coil-forming head having guides therein for strands to be coiled, a core mounted in said head around which core the strands are coiled, and a collar interposed between said head and core for contact with the strands and adapted to rotate under the rotary pull of the strands thereon.

In witness whereof, I have hereunto set my hand this 17th day of April, 1923.

EDWARD TURGEON.
